UNITED STATES PATENT OFFICE.

YEIKICHI OHTSUKA, OF TOKYO, JAPAN.

MINER'S ACETYLENE-LAMP.

1,113,042.

Specification of Letters Patent.

Patented Oct. 6, 1914.

Application filed February 4, 1914. Serial No. 816,640.

To all whom it may concern:

Be it known that I, YEIKICHI OHTSUKA, a Japanese subject, residing at Tokyo, in Japan, have invented certain new and useful 5 Improvements in Miners' Acetylene-Lamps, of which the following is a full, clear, and exact description.

This invention relates to an acetylene lamp whose upper water chamber is connected at its bottom edge with the lower gas generating chamber by a connecting ring. The water drops on the top of a shallow cone-shaped perforated plate from the regulating valve in the bottom of the water 10 chamber, and flows down toward the periphery of the shell along the said perforated plate to be collected in the water groove formed in the connecting ring, for the purpose of keeping the packing material in the 15 bottom of the said groove always in a wet state and perfectly air tight. Then the water flows out from the groove and down along the inside of the shell of the said gas generating chamber, where it combines with 20 calcium carbid and generates acetylene gas.

The object of this invention is to obtain 25 an acetylene lamp for mines which is simple and durable in construction, to maintain the action of lighting always perfect even should 30 the lamp shell be deformed by severe shocking or dropping, or careless treatment in mines, and to hold the connection of two parts perfectly air tight by keeping the connecting part in a continuously wet state by 35 the water dropping down from the water chamber to the gas generating chamber, whereby the escape of gas is prevented.

Reference is to be had to the accompanying 40 drawings forming a part of this specification, in which similar characters of reference indicate corresponding parts in both views.

Figure 1 is a vertical sectional view, partly 45 in elevation of the lamp constructed in accordance with the invention; and Fig. 2 is a plan view thereof.

In Fig. 1, 1 is the water chamber which forms the upper part of the lamp, and 2 is the gas generating chamber forming its 50 lower part, both shells being made by pressing from a metal plate. The water chamber 1 is made up from the outer shell and the bottom plate 3, which has a regulating valve disposed in a central position relative thereto. The valve comprises a screw seat 4 mounted in a depression in the plate 3, and

a screw rod or needle valve 5 threaded thereinto and which has a longitudinal shallow groove 6 in the threaded part, so that the quantity of water may be regulated by screwing the rod in or out, as may be desired. The lower end of the screw rod 5 is conically tapered and it fits a seat around a bottom hole or aperture 7 in the screw seat 4, so the water can be perfectly closed. A shallow 60 cone-shaped perforated plate 8 under the bottom plate 3 has many perforations or holes 9 for escaping gas, and peripheral holes 15 for water, and it is attached to the shell by a tongue piece 10. In this manner 65 the water dropped down from the regulating valve, flows toward the periphery of the shell along the perforated plate 8 and to the water groove 21 in the connecting ring 22.

The connecting part is made up of the 70 connecting ring 22, which has a circumferential water groove 21, the ring being fastened on the upper edge of the gas generating chamber and to the screw ring 11, which is fastened to the lower edge of the water 75 chamber and in turn threaded into the inside of the outer flange 12 of the ring 22, having said circumferential groove. In this manner I provide the connection of the two chambers. The bottom of the groove is 80 stuffed with a packing material 13, and the internal flange 23 of the groove has notches 14 to permit the water to flow out. The water which collects in the water groove 21 keeps the packing material 13 and the contact surface always in wet state, and flows 85 out through the notches 14 and down to the bottom along the inside of the gas generating chamber, where it combines with calcium carbid, and liberates acetylene gas for 90 lighting. Thus the connecting part of two chambers is always kept in wet state to render the connection perfectly air tight, and 95 this is the characterized feature of my invention. The liberated gas passes through the 100 holes 9 in the perforated plate 8 to the gas space 24, where the dust or other impurities are deposited, the gas then passing to the gas burner 16, which has a nozzle 17.

Conveniently, the lamp may be provided 105 with the reflector 18, the port or closed inlet 19 for pouring water into the water chamber, and the carrying handle 20, and the form of the chambers also may be properly modified, as shall be desired, without departing 110 from the spirit of the invention.

Having thus fully described my invention,

what I claim and desire to secure by Letters Patent of the United States is:

1. An acetylene lamp for mine use, comprising an upper water chamber, a lower gas-generating chamber, a connection for the chambers having a groove, means for discharging water from the water chamber to the gas generating chamber, said water passing into the groove to keep the connecting part constantly in a wet state and air tight, and means for effecting the discharge of the gas generated.
2. An acetylene lamp, comprising an upper shell having a bottom dividing wall forming a water chamber, said wall having a discharge opening, means coöperative with the opening to control the dropping of the water therethrough, a lower shell forming a gas-generating chamber, a removable connection between said shells, said connection having a flange producing an interior groove, a packing in said groove, means adapted to receive the water dropped and to discharge the same in the groove to maintain the packing in a wet state, the overflow passing into the generating chamber, and a burner communicating with the gas chamber.
3. An acetylene lamp, comprising an upper shell having a bottom dividing wall

forming a water chamber, said wall having a central discharge opening, means coöperative with the opening to control the dropping of the water therethrough, a lower shell forming a gas-generating chamber, a ring connecting said shells, said connection having a notched flange producing a groove, a packing material in the bottom of the said groove, an apertured cone mounted beneath the discharge opening and extending over the flange whereby the water will flow toward the periphery of the shell and into the groove where it collects to continuously wet the packing material and form an air-tight connection between the shells, the water passing through the notches into the gas-generating chamber, said generating chamber being adapted to contain calcium carbid, which combines with the water to liberate acetylene gas, which escapes through the openings in the cone, and a burner carried by the upper shell and communicating with the gas space above the cone.

In testimony whereof I have signed my name to this specification in the presence of two subscribing witnesses.

YEIKICHI OHTSUKA.
